UNITED STATES PATENT OFFICE.

PAUL RIGOT, JR., OF WHEELING, WEST VIRGINIA.

NECKTIE-FASTENER.

1,273,094.

Specification of Letters Patent. Patented July 16, 1918.

Application filed December 20, 1917. Serial No. 208,019.

To all whom it may concern:

Be it known that I, PAUL RIGOT, Jr., a citizen of the United States of America, and resident of Wheeling, county of Ohio, and 5 State of West Virginia, have invented certain new and useful Improvements in Necktie-Fasteners, of which the following is a specification.

This invention relates broadly to fastening devices, and more particularly to a 10 clasp for neckties.

The primary object of the invention is to provide a tie clasp which is designed for use in the ordinary manner of such devices 15 and which, additionally, embodies means whereby the outer, or exposed, end of the necktie may be secured against lateral movement.

A further object of the invention is to 20 provide a simple, inexpensive and efficient device of the character mentioned, designed especially for use in connection with neckties of the four-in-hand type having a wide flowing or flared end, which embodies a 25 flexible member adapted to maintain said end in position against undue lateral movement and at the same time to permit such slight vertical, or longitudinal, movement as will avoid a stretched condition of the 30 tie and an appearance of too great precisionness or rigidity.

In describing the invention in detail, reference is herein had to the accompanying drawings, in which—

35 Figure 1 is a front end view of a necktie-clasp embodying my invention;

Fig. 2 is a side elevation of the same; and

40 Fig. 3 is a front elevation of the invention partially applied, the outer end of the tie being shown in a detached and laterally displaced position.

Referring to said drawings, in which like designating characters distinguish like parts throughout the several views—

45 1 and 2 indicate the opposing pivoted jaws of a tie clasp which may be of any preferred form. Fixed upon the topmost, or outer, jaw 1 in an appropriate position is a ring or eye-piece 3 to which a knob or button-like 50 head 4 is coupled, said head having attached thereto a link 5 which is received by said eye-piece. Said link is preferably of elongated form and, by preference, is rigidly

connected to and constitutes a shank for 55 said head or button.

The clasp is applied as ordinarily for attaching the smaller or under end 6 of the necktie to the shirt of the wearer. The outer flaring end 7 of the tie must have a slit or button-hole 8 located therein at a suitable 60 point, preferably substantially midway between its lateral edges, and the head or button 4 is directed through this button-hole for securing said tie-end 7 in position. Due to the flexible link connection between the 65 jaw 1 of the clasp and the button, said tie-end 7 is allowed a limited range of freedom of movement which would not be permitted by a button having a rigid connection with the clasp. This is an important feature of 70 the invention, it being desirable that there be an absence of pulling or stretching of the tie with movements of the body of the wearer and also an absence of an appearance of stiffness or rigidity. 75

What is claimed is—

1. A tie fastener comprising a clasp composed of pivoted jaws adapted to be disposed in holding relation to an end of a tie, an eye-piece fixed on the outer of said jaws, 80 a button for engaging the outer free end of a tie held by said clasp, and a relatively long link of loop-form rigidly carried by said button and having its end received in said eye-piece whereby a flexible connection 85 is afforded between said button and said clasp for permitting a limited range of unrestrained lateral and longitudinal movement of said free end of the tie, said button and stem being also designed to occupy suspended position when not in use. 90

2. A tie fastener comprising a clasp composed of pivoted jaws, an eye-piece carried by one of said jaws, and a button having a link of loop form received in the eye of said 95 eye-piece, said button being adapted for introduction through the free end of the tie and to permit the latter to have free relative movement in all directions.

In testimony whereof, I affix my signature 100 in presence of two subscribing witnesses.

PAUL RIGOT, JR.
